CLAIM

The ornamental design for an electronic calculator as shown and described.

DESCRIPTION

FIG. 1 is a top, front, left perspective view of the electronic calculator of my new design;

FIG. 2 is a bottom, rear, right side perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a schematic perspective view of the electronic calculator of FIG. 1 showing the electronic calculator being coupling with the case; and,

FIG. 10 is a schematic perspective view of the electronic calculator of FIG. 2 showing the electronic calculator being coupling with the case.

The broken lines in the drawings depict portions of the electronic calculator that form no part of the claimed design. The broken line showing of the case in FIG. 9 and FIG. 10 is for the purpose of illustrating and forms no part of the claimed design.
